UNITED STATES PATENT OFFICE.

BENJAMIN L. STOWE, OF NEW YORK, N. Y., ASSIGNOR TO J. VAN D. REED,
OF SAME PLACE.

IMPROVEMENT IN TUBULAR KNIT FABRICS.

Specification forming part of Letters Patent No. **222,327**, dated December 2, 1879; application filed September 12, 1879.

To all whom it may concern:

Be it known that I, BENJAMIN L. STOWE, of the city, county, and State of New York, have invented certain new and useful Improvements in Tubular Knit Fabrics, of which the following is a specification.

My invention is directed to a tubular knit fabric designed particularly for fire or hydraulic hose, but also adapted for other uses.

My object is to obtain a fabric which, while equally as strong as, or even stronger than, ordinary fabrics of this kind or class, shall contain less weight of material.

The fabric is characterized by the combination, with longitudinal strands and the ordinary knitting thread or warp, of a spirally-wound weft laid between the said strands and knitting-warp, and an independent warp which binds together the longitudinal strands and the knitting-warp upon the intermediate weft.

By knitting-warp I intend the thread or threads such as are taken by the vertical needles in ordinary knitting-machines.

The independent binding-warp referred to consists of one or more warp-threads independent of the knitting-warp, and taken and operated on by a set of needles independent of that set which operates on the knitting-thread, in such manner that the loops shall extend from the inside to the outside of the fabric.

I prefer to use for the binding-warp two threads, one of which is delivered to its needles at a point within the circle of longitudinal strands, and the other at a point between the longitudinal inner strands of the fabric and the outer knitting-warp.

To enable others to understand and use my invention, I shall describe the machinery which I prefer to employ for the manufacture of my improved fabric, and will then describe the method of making, and the structure of, said fabric.

I would, however, remark that this application for a patent is directed only to the fabric itself. The machine for making it, while here described in so far as necessary to explain my invention, is the subject of a separate application in my name for Letters Patent of even date herewith.

In the accompanying drawings, Figure 1 is a sectional end view of the fabric on an enlarged scale. Fig. 2 is an elevation of a part of the same. Fig. 3 is an elevation of so much of a knitting-machine as is needed to illustrate my invention. Fig. 4 is a vertical central section of the same. Fig. 5 is a plan of the same with the longitudinal strand-guides removed.

B is the upright needle-cylinder on bed A, provided with ordinary latch-needles *a*, attached to blanks *a'*.

C is the upright cam-ring, receiving motion from driving-shaft D through bevel-gears C' C'', all of which, being similar to the corresponding parts in ordinary upright circular-knitting machines, require no further description.

Attached to the upper end of the upright needle-cylinder is a horizontal needle-plate, E, having in its upper face radial grooves, in which horizontal needles *d* and their blanks *d'* slide to and from the center of the machine, each horizontal needle *d* passing midway between the two contiguous vertical needles.

F is the horizontal cam-plate which operates the horizontal needles, and which is attached to and receives its rotary motion from the upright cam-ring C by means of arms F'.

The stitches may be lengthened or shortened by the usual appliances.

From the bed A rises the frame A', which carries two large annular plates, G H, each perforated with a number of holes. Below these plates and carried by the lower one, H, is a third and smaller annulus, I, formed either with a series of perforations or with notches in its inner edge. Usually the number of perforations or notches will equal the number of vertical needles, and the perforations or notches of the lower plate, I, are so placed as to lie in a circle of the same diameter as, or a little smaller than that of, the circle formed by the vertical needles, as shown in Fig. 4.

The devices just described are intended to guide the longitudinal strands or cords 5 to proper position. These strands are carried in any convenient manner from the spools upon which they are wound to a point over the ma-

chine, whence they are brought down through the perforations in plates G H I, passing from the latter plate down into the fabric vertically—that is to say, in a line parallel, or nearly so, with the axis of the machine.

Knitting-warp 2 is supplied to the vertical needles from one or more bobbins, *i*, through hook *j* and eye *k* in arm *k'*, the said bobbins *i*, hook *j*, and arm *k'* being carried by and moving with the horizontal cam-plate F.

The binding-warp, which in this instance consists of two threads, 1 4, is supplied to the horizontal needles through guides *g* and *r*, each of which at its end has an eye through which the thread is delivered.

The guide *g*, which delivers the warp-thread 1, is mounted on and moves with the vertical shaft J, which is hung in proper bearings in frame A' in the prolongation of the vertical axis of the machine, and derives rotary motion from the main driving-shaft through shafts J' J² and bevel-gearing, as indicated in Fig. 3. The shaft rotates at a speed uniform with that of the cam-rings. It carries on an arm, *e*, the bobbin *f*, on which the thread 1 is wound. It also carries on the same arm to which the guide *g* is attached a toothed wheel, *h*.

The warp-thread 1 is delivered by the guide at a point inside the circle of longitudinal strands. The warp-thread 4 is supplied through a suitable guide or guides, as indicated at *r*, from a bobbin, *m*, carried by the horizontal cam-ring F. The guide *r* delivers this warp at a point just outside the circle of longitudinal strands, or between the longitudinal strands and the loops of the knitting-thread of the vertical needles.

The two guides deliver their respective threads in such position that both will be taken by each horizontal needle. The toothed wheel *h* is used to insure that the inner warp-thread, 1, shall be so laid as to be caught by the hook of the needle. Its teeth work in the spaces between the horizontal needles as they would work in a rack.

The weft 3, which lies in a spiral coil between the longitudinal strands 5 within and the knitting-thread 2 without, and has each of its courses bound in place by the loops of the binding-warp, is supplied from a bobbin, *l*, carried by cam ring or plate F. It passes through the tension *n*, or its equivalent, and then to the guide *o*, by which it is deposited. This guide consists of an arm attached to cam-ring F, extending inwardly until it nearly touches the longitudinal strands as they pass to the working-point, and then downwardly at nearly a right angle until its point from which the weft is delivered is just below the level of the horizontal needles.

Sufficient of the machine has been described to indicate one way in which my improved tubular fabric can practically be produced.

The mode of operation is briefly as follows, the parts moving in the direction indicated by the arrow in Fig. 5, and it being supposed that some knitting has already been done in

the machine: The guide *o* deposits the weft 3 at a point below the level of the horizontal needles. The latter, moved properly by their cam, take the binding-warps 1 4 as they are delivered by the guides *r* and *g*, which follow guide *o*, and form the loops which extend from the inside to the outside of the fabric, binding together the longitudinal strands 5 and the knitting-warp 2. The latter, delivered to the vertical-needles' guide *k*, which follows guide *r*, is knitted by said needles in the usual way.

The fabric thus formed is shown clearly in Figs. 1 and 2, the different threads being indicated by their appropriate reference letters or figures.

The fabric is somewhat similar in external appearance to the fabric produced by other machinery of this class, but has less of a groove running longitudinally between the stitches. There are, however, as will be perceived by examination of the figures referred to, radical differences between this fabric and other knit fabrics heretofore made—differences which result in great advantages in respect to strength and durability.

Every stitch or loop has immediately behind it a cord entirely independent of it, and these cords continuously overlap one another, thereby giving increased strength—as, for instance, each stitch of the knitting-warp 2 has behind it the cords of the binding-warp 1 4, as indicated at *x*, and each stitch of the binding-warp has behind it the cords of the knitting-warp 2, as indicated at *y*.

In the structure shown in the drawings, the part of the one warp which backs the stitch of the other warp runs parallel with the weft 3 for some distance, thereby very materially assisting the weft in strengthening the fabric.

Again, in a fabric knit only upon one set of needles, the same cords must enter into every stitch of the same course about the tube, and if a single stitch become cut the stitches upon either side of it are immediately loosened, and the whole of the looped fabric at that point is destroyed; whereas by knitting upon two sets of needles, as described, in combination with the longitudinal strands or cords and the weft 3, in the event of any single stitch being cut there is still behind it another warp, which not only holds the stitches upon either side of it, but prevents the fabric from gaping open at that point.

The additional strength thus obtained, and the improved surface procured in consequence of one longitudinal row of stitches being placed in what would otherwise be a groove between the stitches of the adjoining rows on each side, enables me with less weight of material to make a fabric equally as strong as, or even stronger than, ordinary knit fabrics of this class.

I remark, in conclusion, that while I prefer to use as a binding-warp the two cords or threads 1 4, yet this is not indispensable.

The warp 1, which extends from the inside to the outside of the fabric, may alone be em-

ployed, the prime object being to bind together the knitting-warp and the longitudinal strands upon the intermediate weft.

The warp 4, however, deposited as shown, gives increased strength and durability to the fabric, and can be advantageously used in connection with warp 1.

For some purposes the weft may be deposited outside of the circle of vertical needles instead of within, so as to be held in position by the knitting-warp and binding-warp, either with or without the use of the longitudinal strands; but it is not generally desirable to do so.

Having described my improved tubular knit fabric and one way in which it can practically be produced, what I claim, and desire to secure by Letters Patent, is—

1. In a tubular knit fabric, the combination, substantially as hereinbefore set forth, of longitudinal strands, knitting-warp, and intermediate weft with an independent warp which

is knit into loops independent of and alternating with those of the knitting thread or warp, and binds the said longitudinal strands and knitting-warp together upon the intervening weft.

2. A tubular knit fabric composed of longitudinal strands, knitting-warp, and intermediate weft, in combination with an independent binding-warp whose loops are composed of two cords, or sets of cords, extending to the exterior of the fabric, the one from the interior of the fabric and the other from a point intermediate between the knitting-warp and the longitudinal strands, substantially as hereinbefore set forth.

In testimony that I claim the foregoing I have hereunto set my hand.

BENJAMIN L. STOWE.
